US0D1034994S

(12) **United States Design Patent** (10) Patent No.: **US D1,034,994 S**
(45) Date of Patent: ** Jul. 9, 2024

(54) **ANVIL FOR SURGICAL STAPLER**

(71) Applicant: **Cilag GmbH International**, Zug (CH)

(72) Inventors: **Jie Zhang**, Pudong District (CN);
Joshua Uth, Cincinnati, OH (US); **Anil Nalagatla**, Cincinnati, OH (US);
Bingshi Wang, Cincinnati, OH (US);
Junjie Wang, Zhejiang (CN);
Xiangchun Hong, Shanghai (CN)

(73) Assignee: **Cilag GmbH International**, Zug (CH)

(**) Term: **15 Years**

(21) Appl. No.: **35/515,851**

(22) Filed: **Oct. 6, 2022**

(80) **Hague Agreement Data**

Int. Filing Date: **Oct. 6, 2022**

Int. Reg. No.: **DM/225474**

Int. Reg. Date: **Oct. 6, 2022**

Int. Reg. Pub. Date: **Dec. 23, 2022**

(30) **Foreign Application Priority Data**

(57) **CLAIM**

The ornamental design for an anvil for surgical stapler, as shown and described.

DESCRIPTION

1.1: Front view of an anvil for surgical stapler;
1.2: Back view of the anvil for surgical stapler of 1.1;
1.3: Left view of the anvil for surgical stapler of 1.1;
1.4: Right view of the anvil for surgical stapler of 1.1;
1.5: Top view of the anvil for surgical stapler of 1.1;
1.6: Bottom view of the anvil for surgical stapler of 1.1; and
1.7: Perspective view of the anvil for surgical stapler of 1.1.
The broken lines shown in the figures depict portions of the anvil for surgical stapler that form no part of the claimed design.

1 Claim, 7 Drawing Sheets
